UNITED STATES PATENT OFFICE.

CHARLES A. SAWTELLE, OF DETROIT, MICHIGAN, ASSIGNOR OF ONE-FOURTH TO G. EDWARD HUFF, OF DETROIT, MICHIGAN; ONE-FOURTH TO BERT E. COOK AND ONE-FOURTH TO A. E. LEAS, BOTH OF YPSILANTI, MICHIGAN.

ROTARY VALVE.

Application filed October 23, 1920. Serial No. 419,041.

To all whom it may concern:

Be it known that I, CHARLES A. SAWTELLE, a citizen of the United States, residing at Detroit, in the county of Wayne and State 5 of Michigan, have invented certain new and useful Improvements in Rotary Valves, of which the following is a specification, reference being had therein to the accompanying drawing.

10 This invention relates to a rotary valve for internal combustion engines.

One object of the invention is to provide a simple slow moving rotary valve which will efficiently control both the intake and 15 exhaust for an internal combustion engine and which may be constructed for use with an engine comprising a single cylinder or a plurality of cylinders, with the cylinders cast either individually or en bloc.

20 A further object of the invention is to provide a rotary valve of such a character that the rotary valve member will always be firmly seated about the ports of the valve casing regardless of whether or not it fits 25 tightly in the valve casing.

A further object of the invention is to provide a rotary valve in which both the rotary valve member and the valve casing will be water cooled.

30 A further object of the invention is to provide a rotary valve in which the valve casing will automatically take up wear, and will take care of unequal expansion of the parts.

35 Other objects of the invention will appear as the device is described in detail.

In the accompanying drawings Fig. 1 is a plan view of a rotary valve embodying my invention, progressively broken away 40 to show different parts thereof; Fig. 2 is a side elevation of such a valve, progressively broken away to show different parts thereof; Fig. 3 is a transverse sectional view taken through the valve and the upper portion of a cylinder; Fig. 4 is a plan view of a portion of a valve for a multiple cylinder engine; Figs. 5, 6, 7 and 8 are sectional detail views of the valve showing the valve member in successive positions.

45 In these drawings I have illustrated one embodiment of my invention and have shown the same as comprising a valve casing having a cylindrical valve chamber

which is connected by a port with an engine cylinder and is provided on opposite sides 55 of the cylinder port with an intake port and an exhaust port, respectively. Rotatably mounted within the valve chamber is a valve member having a plurality of peripheral ports arranged circumferentially 60 thereof and spaced apart equal distances. The valve member is rotated, preferably from a moving part of the engine, in timed relation to the movements of the piston so that each of said peripheral ports will be 65 in operative relation to said cylinder port during one-fourth of the cycle of the operation of the engine, and the ports leading to and from the valve chamber are so arranged that the movement of the valve 70 member while each peripheral port is in operative relation to the cylinder port will cause said cylinder port to be first connected with the intake port during the suction 75 stroke of the engine piston, then disconnected from both the intake port and the exhaust port during the compression and power strokes of the piston, and then connected with the exhaust port during the exhaust stroke of the piston. In this manner 80 each peripheral port of the valve serves to control the intake and exhaust to and from the engine cylinder during one complete operation of the engine piston. The several parts of the valve mechanism may 85 take various forms and may be operated in various ways and it will be understood that the particular embodiment of the invention here shown has been chosen for the purposes of illustration only. 90

In that particular embodiment of the invention here illustrated the valve, as a whole comprises a valve casing having a longitudinal cylindrical chamber, or bore, extending lengthwise thereof, and is preferably 95 divided along a horizontal plane into two parts, each of which contains a portion of the valve chamber. The lower portion of the valve chamber, which is indicated at 1, may, if desired, be formed integral with 100 the head, or heads, of the cylinder, or cylinders, 2 with which it cooperates. The upper portion 3 of the valve casing is removably mounted on the lower portion 105 thereof and is preferably provided with reinforcing ribs 4 extending transversely

thereof. The valve chamber is provided with a port 5 leading therefrom to each cylinder 2 of the engine and is also provided, on opposite sides of the cylinder port 5 and spaced relatively short distances therefrom, with an intake port 6 and an exhaust port 7, which communicate respectively with the intake and exhaust manifold of the engine, which are not here shown. Rotatably mounted within the valve chamber is a valve member 8 which is provided in its exterior surface with a plurality of series of recesses, or peripheral ports, 9, the ports of each series being arranged circumferentially of the valve member and spaced apart one from the other such distances that the intermediate portions of the valve member will have sufficient area of contact with the wall of the valve chamber to form tight joints between the valve member and the valve casing. The several series of peripheral ports are spaced apart one from the other distances sufficient to prevent the escape of gases from the ports of one series 25 to the ports of another series.

The valve may be constructed for a single cylinder or for a multiple cylinder engine, and inasmuch as the valve construction for a multiple cylinder engine is merely a duplication of that for a single cylinder engine I will describe the operation of the valve as if it were applied to a single cylinder engine. The rotary valve member is rotated in timed relation to the movements 30 of the engine piston, which is shown at 10, and the number of peripheral ports in each series is determined to a large measure by the speed at which the valve member is rotated. In the present instance, the valve is designed to rotate at one-eighth the speed 35 of rotation of the engine shaft and will, therefore, complete one-fourth of a rotation during each complete operation, of four strokes, of the engine piston, and I have provided the valve member with four peripheral ports in each series. The valve may be rotated in any suitable manner and I have here shown the same as having a part 40 projecting beyond the end of the valve casing and provided with a gear 11 by means of which it may be connected either directly or indirectly with the engine shaft or other suitable operating mechanism. The ports 5, 6 and 7 leading to and from the valve chamber are so arranged with relation one 45 to the other and to the valve member that during each quarter rotation of the valve member one of the peripheral ports 9 will be in operative relation to the cylinder port 5 and the movement of the valve through this quarter rotation will cause the cylinder port to be first connected with the intake port 6, then disconnected both from the intake port and from the exhaust port, and then connected with the exhaust port. Just

prior to the beginning of the suction stroke of the piston 10 the valve member 8 will occupy substantially the position shown in Fig. 5, in which the intake port 6 is in open communication with one of the peripheral 70 ports 9 of the valve member and the cylinder port 5 is closed. With the beginning of the suction stroke of the piston the movement of the valve member will cause the cylinder port 5 to be opened and to be thus 75 connected with the intake port 6. By the time the piston has completed its suction stroke the valve member will have assumed substantially the position shown in Fig. 6, in which the intake port is closed but the 80 cylinder port is still in communication with the same peripheral port 9 of the valve member. During the compression stroke of the piston this same peripheral port remains in communication with the cylinder 85 port but is disconnected from both the intake port and the exhaust port, and consequently, the cylinder port is disconnected from the intake port and exhaust port. At the end of the compression stroke and at the 90 time of ignition the valve will occupy substantially the position shown in Fig. 7, in which both the intake port and the exhaust port are still closed, and it is not until the completion of the power stroke of the piston 95 that the valve member assumes the position shown in Fig. 8 in which it is just ready to open the exhaust port, the same peripheral port 9 being still in open communication with the cylinder port. At the 100 beginning of the exhaust stroke of the piston the exhaust port will be opened and thus connected with the cylinder port to permit the escape of the burned gases from the engine cylinder, and at the end of the exhaust 105 stroke the valve will have again assumed substantially the position shown in Fig. 5 in which the cylinder port is closed and the next succeeding peripheral port of the valve member is in communication with the intake 110 port and in a position to connect this port with the cylinder port upon the further rotation of the valve member.

It will be noted that the ports 5, 6 and 7 all communicate with the valve chamber below the horizontal center thereof and, consequently, the weight of the valve member will hold the same firmly in contact with the walls of the valve chamber about the several ports leading to and from the same at 115 all times, regardless of whether or not the valve member fits tightly within the valve chamber, thus insuring tight joints which will prevent the escape of gas from one port to another between the valve member and the walls of the valve chamber. I have, however, provided means for automatically compensating for or taking up the wear of the valve member and valve casing and to this end the removable upper portion, or cap, 120

3 of the valve casing, which is secured to the lower portion of said casing by means of bolts 12, is yieldably mounted, this being accomplished by interposing springs 13 between the cap and the nuts on the bolts 12. In this manner the cap is held firmly in engagement with the valve member and, further, the cap is permitted to yield to compensate for unequal expansion and contraction of the parts.

The lower portion of the valve casing is preferably water cooled and I have here shown the same as provided with water passages 14 cast integral therewith and adapted to be connected by bosses 15 with the water cooling system of the engine or with any other suitable source of water supply. I also prefer that the valve member itself shall be water cooled and to this end I have formed the same hollow so as to provide it with a water passageway 16 extending lengthwise thereof, and I have provided the end portions of the valve member, beyond the valve casing, with nipples 17 having swivelled connection with the valve member and adapted to connect the same with the water cooling system of the engine or any other suitable source of water supply. I have also provided the valve member within the water passageway 16 with a device to cause circulation of the water independently of the circulation of the water in the cooling system of the engine, and to this end I have mounted at one end of the valve member and within the passageway 16 vanes 18 which are set at such an angle that they will cause the water to circulate within the valve.

The upper portion, or cap, 3 of the valve casing has formed therein a longitudinally extending oil conduit 19 which is connected by means of ports 20 with the valve chamber at points between adjacent series of peripheral ports in the valve member. The conduit 19 may be connected with any suitable source of oil supply and the oil will circulate through the conduit and ports 20 to the interior of the valve structure, thus providing adequate lubrication for the same.

The operation of the valve will be readily understood from the foregoing description and it will be apparent that I have provided a very simple slow moving valve which will efficiently control the intake and exhaust for the engine cylinder and which is of such a character that it is readily adaptable for use in either a single cylinder or multiple cylinder engine. Further, it will be apparent that I have provided means for so cooling both the valve member and the valve casing as to prevent excessive inequalities of expansion and contraction, and that I have so constructed the valve casing as to permit of a certain amount of unequal expansion and contraction. It will be apparent that

the upper portion or cap 3 of the valve casing is separate from the lower water cooled portion of the casing and that its chamber will be effected but little, if any, by the circulation of the water in contact with the lower portion of the valve casing. As a result the cap receives its heat from the valve member itself and is free to expand and contract in direct proportion to the heat thus transmitted to it by the valve member and consequently to an extent substantially equal to the expansion and contraction of the valve member, thereby maintaining at all times a substantially uniform clearance between the valve and the casing. The reinforcing ribs 4 will serve as heat radiating fins so that the cap will to a certain extent be air cooled. When the engine is first started into operation the valve will be quickly heated because of the direct contact of the hot gases therewith and this heat will be transmitted to the separate cap of the valve casing so that the cap will expand to substantially the same extent as the valve. The cap will not become overheated because the valve itself is water cooled and will not transmit sufficient heat to the cap to overheat the same although the cap is cooled only to a limited extent by air. Further, it will be apparent that all parts of the cap are free to expand and contract and if one part of the valve is cooled to a greater extent than the other, thus causing an uneven expansion thereof, the cap will also be unevenly heated and will expand in the same manner and to the same extent as the valve expands.

While I have shown and described one embodiment of my invention I wish it to be understood that I do not desire to be limited to the details thereof as various modifications may occur to a person skilled in the art.

Having now fully described my invention, what I claim as new and desire to secure by Letters Patent, is:

1. In an internal combustion engine, a cylinder, a valve casing carried by said cylinder and having a cylindrical chamber, said casing having an inlet port, an outlet port and a port connecting said chamber with said cylinder, a valve rotatably mounted in said chamber and having a peripheral port to successively connect said cylinder port with said inlet port and said outlet port, and means for cooling said cylinder, said valve casing comprising a cap which is independent of said cooling means and the temperature of which is controlled by said valve, said cap being free to expand and contract uniformly with said valve and thereby maintain a uniform clearance between the same and said valve.

2. In an internal combustion engine, a cylinder, a valve casing carried by said cylinder,

der and having a cylindrical chamber, said casing having an inlet port, an outlet port and a port connecting said chamber with said cylinder, a valve rotatably mounted in said chamber and having a peripheral port to successively connect said cylinder port with said inlet port and said outlet port, and means for circulating water in contact with said cylinder and the lower portion of said 5 valve casing and through said valve, said casing being divided longitudinally to provide a cap which is separate from and detachably secured to the lower portion of said casing and the temperature of which is controlled by said valve, said cap being free to expand and contract uniformly with said valve and thereby maintain a uniform clearance between the same and said valve.

3. In an internal combustion engine, a cylinder, a valve casing carried by said cylinder and having a cylindrical chamber, said casing having an inlet port, an outlet port and a port connecting said chamber with said cylinder, a valve rotatably mounted in said chamber and having a peripheral port, means to rotate said valve in a direction to move said peripheral port from said inlet port past said cylinder port to said exhaust port, and means for cooling said cylinder, said valve casing comprising a portion constituting a cap which is independent of said cooling means and the temperature of which is controlled by said valve and the exhaust gases carried into contact therewith by said peripheral port, said cap being free to expand and contract uniformly with said valve and thereby maintain a uniform clearance between the same and said valve.

4. In an internal combustion engine, a valve casing having a cylindrical chamber, means for cooling a portion of said chamber, and a valve rotatably mounted in said chamber, said casing being divided longitudinally to provide a cap separate from said cooled portion of said casing and independent of said cooling means, all parts of said cap being free to expand and contract under the influence of heat transmitted to it by said valve and uniformly with the expansion and contraction of said valve.

5. In a rotary valve for an internal combustion engine, a valve casing having a cylindrical chamber, a port leading from said chamber to the cylinder of the engine, intake and exhaust ports communicating with said chamber on opposite sides of said cylinder port, a valve rotatably mounted in said chamber and having a plurality of peripheral ports arranged circumferentially thereof, and means for rotating said valve in timed relation to the movements of the piston of said engine to cause said peripheral ports to be moved successively into operative relation with said cylinder port, said

65 peripheral ports being so arranged and the rotation of said valve so timed as to cause each peripheral port to be in operative relation to said cylinder port during the four strokes of said piston, and to cause said cylinder port to be first connected with the 70 intake port during the suction stroke of the piston, then disconnected from both the intake port and the exhaust port during the compression and power strokes of this piston, and then connected with the exhaust 75 port during the exhaust stroke of the piston.

6. In a rotary valve for an internal combustion engine, a valve casing having a cylindrical chamber, a port leading from said chamber to the cylinder of the engine, intake and exhaust ports communicating with said chamber on opposite sides of said cylinder port, a valve rotatably mounted in said chamber, and having four peripheral 80 ports spaced equal distances apart about the circumference thereof, and means for moving said valve through one-fourth of a rotation during each four strokes of the piston of said engine, the ports in said valve casing being so arranged with relation to said peripheral ports that said one-fourth rotation of said valve will cause the cylinder port to be first connected with the intake 85 port during the suction stroke of the piston and then disconnected from both the intake port and the exhaust port during the compression and power strokes of the piston, and then connected with the exhaust port during the exhaust stroke of the piston, each 90 peripheral port remaining in communication with said cylinder port during the four 95 strokes of said pistons.

7. In a rotary valve for an internal combustion engine, a valve casing having a cylindrical chamber, a port leading from said chamber to the cylinder of the engine, intake and exhaust ports communicating with said chamber on opposite sides of said cylinder port, a valve rotatably mounted in said chamber and having a plurality of peripheral ports arranged circumferentially thereof, said intake port and said exhaust port being spaced respectively from said cylinder port distances greater than the distances between adjacent peripheral ports in said valve, and means for rotating said valve member in timed relation to the movements of the piston of said engine to cause said peripheral ports to be moved successively 105 into operative relation to said cylinder port and to cause said valve to be so operated that each port will be in operative relation to said cylinder port during the four strokes of the 110 piston of said engine.

115 In testimony whereof, I affix my signature hereto.

CHARLES A. SAWTELLE.
